(57) **CLAIM**

The ornamental design for a modern lever, as shown and
described.

DESCRIPTION

FIG. 1 is an upper-left front perspective view of a modern lever.

FIG. 2 is a lower-right rear perspective view of the modern lever.

FIG. 3 is a front view of the modern lever.

FIG. 4 is a right side view of the modern lever.

FIG. 5 is a top view of the modern lever.

FIG. 6 is a bottom view of the modern lever.

FIG. 7 is a left side view of the modern lever; and,

FIG. 8 is a rear view of the modern lever.

The broken lines shown represent unclaimed subject matter
and form no part of the claimed design.
